US0D1043658S

(12) **United States Design Patent** (10) **Patent No.:** **US D1,043,658 S**
(45) **Date of Patent:** **** Sep. 24, 2024**

(54) **INFORMATION HANDLING SYSTEM**

(71) Applicant: **Dell Products L.P.**, Round Rock, TX (US)

(72) Inventors: **Ya Sang Fong**, Linkou District (TW); **Joshua Y. Probst**, Austin, TX (US); **Jihun Yeom**, New Taipei (TW); **Ivan Hsich**, New Taipei (TW); **Ian Li**, Da'an Dist. (TW); **Nathaniel Overholtzer**, Austin, TX (US)

(73) Assignee: **Dell Products L.P.**, Round Rock, TX (US)

(**) Term: **15 Years**

(21) Appl. No.: **29/814,105**

(22) Filed: **Nov. 3, 2021**

(51) LOC (14) Cl. **14-02**

(52) U.S. Cl.

USPC **D14/315**; D14/327

CLAIM

We claim the ornamental design for an information handling system, as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a front perspective view of the information handling system in an open position; and,

FIG. 10 is a bottom perspective view of the information handling system in an open position.

Broken lines shown in the drawings illustrate portions of the information handling system and form no part of the claimed design.

1 Claim, 8 Drawing Sheets
